tion of Delaware

Application October 18, 1934, Serial No. 748,846

11 Claims.

(Cl. 93—3)

This invention pertains in general to packaging equipment and specifically relates to a form of automatic packaging machine.

One of the objects of the invention is to provide a construction of packaging for effecting a continuous and rapid process in the production of packages.

A further object of the invention consists in producing a machine organization for the fabrication of packages having individual commodity-containing enclosures for packaged commodities.

A further object of the invention comprises providing a construction of packaging machine utilizing a plurality of sources of packaging material utilized in a continuous heat sealing packaging operation for producing packages of a novel character.

These and other objects reside in a construction of packaging machine and a method of manufacture as will be readily apparent from the following description in conjunction with the appended drawings in which like reference numerals designate corresponding parts and in which:

Fig. 1 is a front view, partially sectioned, of the central portion of one embodiment of a packaging machine according to this invention;

Fig. 2 is a vertical sectional view taken centrally of the representation of Fig. 1;

Fig. 3 is a longitudinal sectional view of the composite heating, crimping and pressing equipment employed in the invention;

Fig. 4 is a plan view of a typical package which may be fabricated by the machine here disclosed;

Fig. 5 is a side view of the package structure of Fig. 4.

This invention contemplates the use of a plurality of feeder rolls of packaging material which are positioned for feeding toward centrally positioned sealing and crimping equipment associated with a feeding mechanism which permits a continuous and rapid manufacturing process in the fabrication of packages of the type indicated. The feeding mechanism cooperates with the sealing and crimping equipment to properly position commodity articles between opposed layers of the packaging material at spaced intervals, while the sealing equipment crimps the packaging material together at areas other than those occupied by the package, at the same time heating these areas in an oxidation process to form, by rapid production methods, a novel form of package.

Referring to the drawings in detail and par-

ticularly to Fig. 1, there is provided a general mounting structure 1, having two reel spindles 2 and 3 positioned upon opposite sides thereof. Mounted upon these reel spindles 2 and 3 are reels 4 and 5, respectively. These reels 4 and 5 are provided with central cores upon which rolls of packaging material 6 and 7 are respectively stowed for rotatable feeding purposes. The packaging material so provided is preferably of transparent strip or ribbon formation and is of a composition such as regenerated cellulose, with a heat treatment coating thereon, although other material may be employed. Extending from the rolls 6 and 7 are leader strips 8 and 9, respectively. These leaders feed into the heating and sealing equipment described in more detail later.

Upon an upper portion of the mounting structure 1 there are provided two pressure members 11 and 12 in the form of bars pivotally mounted so as to engage in peripheral contact with the reels 6 and 7 to maintain the proper tension on the leader strips and avoid uncoiling of the rolls of packaging material. These members 11 and 12 are provided with longitudinal slots, not shown, within which hand adjustable weight members 13 and 14 may be adjustably positioned. These weight members, when adjusted back and forth in their respective slots, regulate the pressure applied to the rolls 6 and 7 to maintain the proper tension for different types of material.

The leader strips 8 and 9 extend centrally of the mounting structure in directions toward each other and pass over idler rollers 15 and 16 and thence to the package forming and sealing equipment. This equipment includes a pair of rollers 17 and 18 which combine several functions in their action and will now be considered in detail. Each roller is provided with two annular rows of peripheral recesses 19, and, in the present representation, there are six recesses in each row whereby each roller is provided with twelve recesses in all. It will be understood, of course, that the number of recesses and rows of recesses may be varied to meet various packaging requirements.

Referring also to Fig. 2, the rollers 17 and 18 are provided with a plurality of stripper fingers 21 which are secured to a boss 22 on the general mounting structure 1. These stripper fingers are positioned in annular slots in the reels 17 and 18, so as to occupy positions behind the recesses 19 at the point of intersection of the rollers 17 and 18. The purpose of these stripper fingers 21 is to guide the leader strips 8 and 9 into and

5

55

out of the rollers 17 and 18 and particularly to avoid a tendency of the packaging material to wrap around the rollers.

In the area surrounding the recesses 19 on the rollers 17 and 18, there is provided a cross-hatched crimping surface. The crimping surfaces of the rollers 17 and 18 are complementary to each other and mesh with one another to produce an interdigititation of the opposed layers of packaging material fed by the rollers. However, the crimping area surrounding the recesses 19 is interrupted at spaced intervals and provided with complementary cutting knives which will be better understood in connection with the description of the product formed by the machine, as will be hereinafter pointed out.

The rollers 17 and 18 are secured upon shafts 24 and 25 which are rotatably mounted through bearings in the boss 22. Referring to Fig. 3, 20 it will be seen that the shaft 24 is hollow for a portion of its length coextensive with the roller 17. In this hollow portion a heater cartridge 26 is provided which includes a resistance element for heating the roller 17 to a temperature sufficient to cause oxidation and a physiochemical change in the regenerated cellulose packaging material when in contact therewith. At the outer extremity of the shaft 24 an insulating element 27 is provided with collector rings which 30 connect with opposite terminals of the heater cartridge 26. The collector rings on the element 27 are engaged by contact brushes respectively carried by a terminal mounting 28 secured to the boss 22 by mounting element 29. The terminal 35 mounting 28 is provided with suitable leads so that electrical energy may be supplied in the proper amount to the heater element internal of the roller 17. The roller 18 is provided with a similar heating arrangement.

40 To effect the complementary rotation of the rollers 17 and 18, the shafts 24 and 25 are provided with gears 30 and 31, respectively, as is shown in dotted line in Fig. 1. These two gears engage each other so as to cause the rotation of 45 the rollers 17 and 18 in timed relationship with respect to other moving parts of the packaging machine and with respect to each other in a manner such that the recesses 19 coincide with each other as the rollers 17 and 18 are rotated 50 in opposite directions. The crimping surfaces of the rollers 17 and 18 then mesh with each other in a complementary fashion to cause a forced interdigititation of the layers of packaging material fed therebetween.

55 Referring to Fig. 2, the shaft 25 extends through a bearing and boss 32 in a rear wall of the mounting structure 1. The shaft 25 is coupled through bevel gears 33 and 35 to a shaft 36. The shaft 36 is journaled in a bearing member 37 and terminates in a clutch driven-member 38. Another shaft 39 is mounted in alignment with the shaft 36 and is mechanically coupled through suitable reduction gearing with an electric driving motor not shown in the drawings. 60 The shaft 39 is provided with a clutch driving-member 40 for engagement with the clutch driven-member 38. The clutch driving-member 40 is associated with a shift collar 42 mounted on the shaft 39 in a manner such as to receive 65 rotary movement while being susceptible to axial movement along the shaft 39. A shift yoke 43 mechanically engages the collar 42 for imparting this axial movement to permit engagement and disengagement of the members 38 and 40 under 70 control of a handle 44, as shown in Fig. 1. The

handle 44 can be actuated to selectively drive the operating mechanism of the packaging machine as desired while maintaining a continuous operation of the driving motor.

Consideration will now be given to the commodity feeding mechanism employed in the package fabricating organization. In the present invention, this mechanism is shown as being particularly designed for feeding commodity articles such as medicinal pellets and the like, but it is to be understood that modifications can be made to fit other types of articles without departing from the scope of the invention.

A commodity releasing structure 45 is positioned directly above the intersection of the two 15 rollers 17 and 18. This structure has an internal chamber through which the pellets 46 feed by gravity from a connected chute or throat 47 extending upwardly therefrom. This throat 47 is of the type having an open portion for permitting access to the commodity feed line. At its upper extremity, the throat connects with a suitable form of storage hopper for depositing the commodity articles in the throat and which does not, in itself, form part of the present invention.

At the outer extremity of the releasing structure a retaining spring 48 is positioned to retain the pellets 46 in a position such that the end-most pellet in the line of pellets is prevented from falling through a hole 49 in the bottom of the release structure. This hole 49 is directly in alignment with opposed rows of recesses 19 in the rollers 17 and 18. Another hole is provided in the upper portion of the release structure in alignment with the other rows of recesses 19. However, this hole is normally occupied by a trap member 51 which, as shown in Fig. 1, is pivoted to an upward extending portion 52 of the release structure 45. A spring 53 normally holds this trap member 51 in a position such as to occupy 40 this hole in the under portion of the release structure 45, thereby preventing the pellets 46 from falling through into the crimping rollers.

Reciprocatively mounted through the upper portion of the release structure 45, is a bifurcated 45 plunger member 54, the legs of which are in respective alignment with the two rows of recesses in each of the rollers 17 and 18. The plunger member 54 is pivotally suspended from two bars 55 and 56, mounted on pivot rods 57 50 and 58 extending transversely between walls of the general mounting structure 1. The bars 55 and 56 coact to impart substantially rectilinear reciprocal motion to the plunger member 54 through the release structure 45.

The plunger member 54 is provided on one side with an extension 59 adapted to engage with a projection 61 on the pivoted trap member 51 so that a downward movement of the plunger 54 causes the trap member 51 to be pushed aside 60 against the action of spring 53, thereby permitting a pellet to fall through the hole in the under portion of release structure 45, normally occupied by the trap member 51. Simultaneously with such an operation, one leg of the bifurcated 65 plunger 54 engages with the spring 48 to force the same out of position and permit the end-most pellet 46 to fall through the hole 49, the adjacent leg of the bifurcated plunger 54 acting to push the pellet therethrough. At the same time the other leg of the bifurcated plunger 54 follows a pellet through the hole initially occupied by part of the trap member 51. The two legs of the bifurcated member 54 follow through to position the pellets with respect to the package material 70

being fed through the rollers 17 and 18. A specially formed cam 62, mounted on the shaft 25, engages with a rider 63 secured to one end of the bar 56 to impart a specially timed reciprocative motion to the plunger 54. This motion is of a nature such that when recesses in the crimping rollers 17 and 18 are approaching a horizontal line extending through the axes of both rollers, so as to receive pellets from the release structure 45, the plunger 54 is made to effect the release of two pellets and follow these pellets through, thereby holding them in position between the opposed layers of packaging material for a time until the subsequent rotation of the rollers 17 and 18 produces a closed condition of the opposed recesses in the rollers more in a horizontal alignment whereupon the plunger member 54 is withdrawn to resume its normal upward position.

When returned to its normally upward position, the legs of the plunger member 54 have been withdrawn from the internal passageway of the release structure 45 so that the line of pellets is moved down by gravity to position further pellets for insertion between the crimping rollers 17 and 18. It will be particularly noted that the distance between the rows of recesses in either of the rollers, and the spacing between the first and third pellets of the file is substantially the same. Such a spatial arrangement utilizes the intervening or second pellet for spacing purposes before its subsequent use in the package. Thus, a single feed line of file formation is utilized to permit multiple transfer of articles therefrom into a multiple formed package structure.

Bar 55 is provided at its rearward extremity with a suitable tension spring 64 in conjunction with an adjusting member 65 for imparting a force through the plunger 55 to the bar 56 to effect the continuous peripheral engagement of the rider 63 with cam 62.

In accordance with this invention there is also provided an arrangement for severing the fabricated package structure at timed intervals to produce composite package units. The time of severance is so determined that all of the package units are preferably of similar structure and cut at the same place. In considering this severing equipment in detail, there are provided two stationary cutting members 66 and 67, rigidly fixed to the bottom of the boss 22 and upon opposite sides of the course taken by the package structure as it emerges from between the two rollers 17 and 18. Beneath the two stationary cutting members 66 and 67, and in abutting relationship thereto, there is provided a movable knife member 68, mounted upon a shaft 69 rotatably positioned in bearing 70. The bearing 70 is secured to a front wall of the general mounting structure 1. A coil spring 72 is provided on the shaft 69 between the bearing 70 and knife member 68 for urging the latter into a predetermined position.

At the lower extremity of the shaft 69 a gear 73 is provided. This gear 73 engages with a toothed gear sector 74 which forms one end of a lever 75. This lever has a fulcrum point at the pivot bearing 76 and has a projecting end 77 provided with a follower element 78. The follower 78 engages in a groove in a type of cylinder cam 80. The cam 80 is mounted upon a shaft 81 extending through a suitable bearing in the rear wall of the general mounting structure 1 and which terminates in a gear 82. The gear 82 engages with an intermediary gear 83 in turn engaging with a driving gear 84 mounted upon the

outer extremity of the shaft 25. These gears are of an easily demountable type for permitting substitution of different gear ratios in order to obtain different driving effects of the cam 80. The cam 80 and groove therein, together with the driving gears therefore, are so constructed that a reciprocative motion is transmitted through the lever 75 and sector 74 to the gear 73. This reciprocative motion produces a quick shearing effect between the knife member 68 and the cutting members 66 and 67. This reciprocative shearing effect severs the finished package structure into composite units. These units may be of any desired length depending on the adjusted timing of the knife 68. As the package units are severed by the knife action they may fall into a suitable hopper or conveyer provided for the purpose.

More detailed consideration will now be given to the package structure itself as produced by the packaging organization. Referring to Fig. 4, it will be seen that pellets 46 are disposed in longitudinal rows between two layers of regenerated cellulose. This cellulose material has been interdigitated by the complementary crimping surfaces of the rollers 17 and 18 in areas surrounding each of the pellets 46. It will be noted that the crimping area surrounding each pellet is in the form of a square and that the squares for the various pellets are interrupted by a separation line "A" extending longitudinally of the package material and also by separation lines "B" extending transversely of the material. These separation lines divide each of the pellets and its accompanying packaging material into individual squares. At the edge of each of the separation lines "B", a perforation 86 is provided, while at the intersection of the separation lines "B" with the separation lines "A", cross-perforation lines 87 are provided. The perforations extend entirely through both layers of the cellulose material and permit the easy separation of each of the package units from the composite package unit as a whole so that the consumer can detach a square containing one pellet for individual use. Other separation lines "C" are provided running through the rows of commodity-containing recesses. All of the perforations of the package structure are effected in the packaging material as they pass between the rollers 17 and 18, due to a cutting action of these rollers. It will be noted that knife elements 90 are provided on the roller 17. These knife elements engage with complementary portions of the roller 18 and cut the packaging material to produce the perforations 86 as the package material passes between the rollers. Other knife elements are provided on the rollers 17 and 18 to effect a perforation of the package at the intersection of the separation lines "B" with the separation line "A".

It will now be seen that the rollers 17 and 18 simultaneously perform a multitude of operations consisting of the feeding of the packaging material, the positioning of the commodity articles between opposed layers of the material, the interdigitation of the layers under pressure in areas surrounding the commodity articles, and the heating of these areas within a range to produce oxidization and physicochemical change of such areas to assume an embrittled character susceptible to easy tearing for promoting facile removal of the commodity articles from the packaging material. The package thus produced utilizes the normal tough and wiry nature of the regenerated cellulose for article containing envelope

areas, while the seal or bond areas surrounding the same are of an embrittled nature for gaining easy access to the envelope enclosure areas.

The machine in its entirety is operable for producing the continuous and rapid fabrication of package units each containing individual commodity articles maintained in sealed and segregated spaced relationship. It will be noted that a plurality of sources of package material are used for feeding opposed layers of the coated regenerated cellulose material into the heating and crimping rollers 17 and 18. The commodity article feeding mechanism cooperates with the crimping rollers in timed relationship to deposit the commodity articles between the opposed layers of packaging material. It will be noted in this respect that the plunger element 54 has four cycles of operation. In the first cycle, the plunger is in an up-raised condition wherein the pellets 46 move into an initial position as fed through the throat 47; in the next cycle of operation, the plunger 54 effects the release of a pair of these pellets and at the same time follows them through into a position between the opposed layers of packaging material in which opposed recesses of the rollers 17 and 18 engage with the pellet; in the next cycle of operation, the plunger 54 remains in this lower position until the recesses of rollers 17 and 18 have rotated sufficiently to properly secure the deposited pellets in closed relation between the packaging material. The plunger element 54 then completes its last cycle of operation by returning to its initial upward position and permitting the file of pellets to again be moved into a position ready for a repeat operation.

The completed package as fed from between the rollers is then severed at desired positions by the knife element 68, the action of the knife element 68 being timed so that the package material is severed directly on one of the separation lines "B" extending transversely of the packaging material strips. Of course, the timing may be adjusted so that the severing may occur to produce a unit having any number of individual package squares therein. For example, a package unit with 2, 4, 6, 8 or more squares can be produced. In another form of my invention, it may be desirable to provide crimping and heating rollers in a different arrangement in which there are more or less rows of recesses 19 to produce different forms of packages. Recognizing that such modifications are within the purview of those skilled in the art, the present embodiment has been shown of a compound form for feeding articles to two rows of recesses which form is considered a typical example of operation.

All of the operable elements work in an inter-related timed sequence driven from an electric motor which is not shown in the drawings. The clutch may be operated by the hand lever 44 to engage or disengage the driven elements from the motor as desired. The supply means for delivering the commodity articles to the throat 47 may be of any suitable type and may include movable parts such as a rotating drum and movable agitator, all of which may be driven, if desired, from the electric motor such as through a continuation of the shaft 36.

Although the invention has been described in a preferred form, it will be understood that various modifications and changes will occur to those skilled in the art. It is therefore not intended that any limitations be attached to the fore-

going other than those pointed out in the appended claims.

What I claim as new and desire to secure by Letters Patent of the United States is:

1. A package forming machine comprising means for supplying and feeding a packaging material in opposed layers, article feeding means for depositing commodity articles between said opposed layers and comprising, a chute for supplying commodity articles in file formation and including a release arrangement for simultaneously releasing a plurality of articles therefrom in predetermined spaced relationship, means for periodically operating said release means; and package forming means including bonding equipment for joining said layers in spaced areas surrounding said articles, said bonding equipment comprising complementary rotatable rollers having heating elements for causing said rollers to heat said packaging material restrictively in said areas surrounding said articles. 5 10 15 20

2. A package fabricating machine in accordance with claim 1 in which said package forming means includes a severing device for severing predetermined portions of said layers at points intermediate said commodity articles enclosed there-between. 25

3. A package fabricating machine in accordance with claim 1 in which said article feeding means comprises a release chamber, a throat for feeding individual articles thereto in a continuous file, and means for releasing alternate pairs of articles from said file into a position intermediate said layers of material, the articles intermediate said pairs acting as spacers until in turn transferred from said release arrangement. 30 35

4. A package fabricating machine in accordance with claim 1 in which said article feeding means comprises a release chamber, a throat for feeding commodity articles thereto in continuous file, and release means for releasing selected articles from said file, said release means including plunger means operable to follow said articles into a position intermediate said layers of material. 40 45

5. A package fabricating machine comprising, a general mounting structure, means carried thereby for supporting rolls of strip packaging material, rollers carried by said general mounting structure and provided alternately with recesses and bonding areas, means for supporting and driving said rollers in complementary engagement so that said recesses coincide with each other in the concomitant rotation of said rollers, article feeding means including a release chamber, a throat for supplying articles thereto in file formation, and plunger means operable through said release chamber for transferring articles therefrom to a position intermediate said rollers, a cam for effecting the reciprocal movement of said plunger means in a four-movement operation, as follows: first, to permit said articles to enter said chamber; second, to operate through said chamber to release articles therefrom; third, to hold said articles in a position intermediate said rollers; and, fourth, to return to said initial position; and means for driving said cam in timed relationship with the rotation of said rollers. 50 55 60 65

6. A package forming machine in accordance with claim 5 including severing means for cutting said strips of packaging material after bonding at points intermediate said articles held there-between, said severing means comprising relatively movable elements, cam means for effecting said relative movement, and means for driv- 70 75 75

ing said cam means in timed relationship with the rotation of said rollers.

7. A packaging apparatus comprising, means for feeding opposed layers of packaging material, package forming equipment having mutually engageable parts for sealing said layers of material together, means for storing commodity articles in file formation, transfer means for transferring said articles from said storage means to a point between said layers of material in engagement with said mutually engaging parts of said package forming equipment, and having parts thereof for holding said transferred articles in said position, said package forming equipment operating to seal said transferred articles between said layers of material.

8. A packaging apparatus comprising, a pair of rotative elements having alternate recesses and sealing surfaces, said elements being mounted for rotation with the recesses and sealing surfaces coming into respective mutual engagement in rotation, means for feeding opposed layers of sealable packaging material between said rotative elements, storage means for storing articles in file formation, transfer means for transferring articles from said storage means to a position between said layers of material adjacent said rotative elements, and mechanically interconnected driving means for causing said transfer means to transfer said articles to said position between said layers of material at a time when the op-

posed recesses of said rollers are coming into alignment whereby said recesses engage said article through said layers to remove the same from said transferred position and seal said layers with said sealing surfaces to enclose said articles in said layers.

9. The apparatus in accordance with claim 8 in which said transfer means includes parts for holding said transferred article in said transferred position for a predetermined time during which said recesses operate through said layers of material to remove said article from said transferred position in a package forming operation.

10. Apparatus in accordance with claim 8 in which said transfer means comprises a plunger for selectively removing articles from said file formation, said plunger acting to follow a selected article to said transferred position and hold said article in said transferred position until caught by said rotative element.

11. The apparatus in accordance with claim 8 in which said storage means positions said articles in file formation in the plane of engagement of said rotative elements, and in which said transfer means operates to release selected articles from said file formation to be deposited in a predetermined position intersecting said rotative elements.

LEROY L. SALFISBERG. 30
